UNITED STATES PATENT OFFICE.

ISAAC B. FRANTZ, OF ALLENPORT, PENNSYLVANIA.

TELEGRAPH-INSULATOR.

SPECIFICATION forming part of Letters Patent No. 619,555, dated February 14, 1899.

Application filed August 4, 1898. Serial No. 687,702. (No model.)

To all whom it may concern:

Be it known that I, ISAAC B. FRANTZ, a citizen of the United States of America, residing at Allenport, in the county of Washington 5 and State of Pennsylvania, have invented certain new and useful Improvements in Telegraph-Insulators, of which the following is a specification, reference being had therein to the accompanying drawings.

10 My invention relates to certain new and useful improvements in insulators.

The object of my invention is to provide a device of this character which will dispense with the usual winding of the wire and securing 15 or clamping the same thereto to the insulator.

My invention consists in constructing an insulator of this class of a supporting-pin having a positioning-plate for the wires mounted 20 thereon and a securing-cap therefor.

25 My invention further consists in the novel combination and arrangements of parts hereinafter more specifically described, illustrated in the accompanying drawings, and particularly pointed out in the claim.

In describing the invention in detail reference is had to the accompanying drawings, in which—

30 Figure 1 is a perspective view of a pair of my improved insulators in position, having the wires secured thereto. Fig. 2 is a side view of one of the insulators. Fig. 3 is a vertical sectional view thereof, the cross-arm also being partly in section. Fig. 4 is a top plan 35 view of the positioning-plate, showing the grooves formed thereon for the reception of the wires. Fig. 5 is a perspective view of the positioning-plate. Fig. 6 is a cross-sectional view thereof.

40 Referring to the drawings, in which like numerals of reference indicate corresponding parts throughout the several views thereof, I indicates the cross-arm for the pole, which has formed therein a suitable screw-threaded 45 aperture to receive the screw-threaded end 2 of the supporting-pin 3. This supporting-pin is cut away, as at 4, thereby forming a series of extensions or lugs 5. Formed integral with the upper face of the supporting-pin is a 50 screw-threaded fastening-pin 6, which is of suitable length. The supporting-pin may be

Y-shaped, as shown, or any other suitable configuration desired.

Mounted upon the upper face of the supporting-pin is a positioning-plate 7, which is 55 apertured, as at 8, for the insertion therethrough of the fastening-pin 6. The upper face of the positioning-plate is formed with a series of grooves 9 for the positioning of the wire thereon and also for assisting in keeping 60 the same in position and preventing the slipping of the same. The grooves are vertical, horizontal, and oblique to allow the wire to be positioned in any direction. The lower face thereof is cut away, as at 10, thereby 65 forming extensions or lugs 11. The cut-away portion 10 is adapted to receive the extensions 5 of the supporting-pin, and the cut-away portions 4 are adapted to receive the extensions 11 of the positioning-plate. This 70 prevents the revolving or moving of the positioning-plate when it is mounted on the supporting-pin.

For the purpose of securing the wire 12 in position when it is placed in the grooves on 75 the positioning-plate I provide a securing-cap 14, which has an elongated screw-threaded slot 15 and which is adapted to be secured on the fastening-pin 6.

I construct the lower face of the securing- 80 cap and upper face of the positioning-plate concaved, as shown, to allow the water to drain therefrom.

My device may be constructed of any suitable material; but I prefer to construct the 85 securing-cap and positioning-plate of glass and the supporting-pin of wood.

It is readily apparent that when it is desired to secure the wires to the insulator the wires are placed in the suitable groove on the 90 positioning-plate and the securing-cap is screwed upon the same, thereby securely holding the same in position. This prevents the usual method of winding and clamping the wire upon the insulator.

95 It will be noted that various changes may be made in the details of construction without departing from the general spirit of my invention.

Having thus fully described my invention, 100 what I claim as new, and desire to secure by Letters Patent, is—

In an insulator for telegraph-wires the combination of a supporting-pin, a fastening-pin formed integral with and extending upwardly from the upper face thereof, a convex grooved 5 positioning-plate for the wire having its upper face formed with a series of positioning-grooves adapted to be mounted on said fastening-pin, extensions formed integral with the lower face of said positioning-plate to 10 prevent its movement when mounted upon the fastening-pin, and an interiorly-screw-

threaded securing-cap adapted to be mounted upon the fastening-pin to securely hold the wire and positioning-plate in position, substantially as shown and described.

In testimony whereof I affix my signature in the presence of two witnesses.

ISAAC B. FRANTZ.
